UNITED STATES PATENT OFFICE.

STANLEY LASIEWICZ AND PAUL LASIEWICZ, OF THREE LAKES, WISCONSIN.

METALLIC TIE AND RAIL-FASTENER.

1,223,805.

Specification of Letters Patent. Patented Apr. 24, 1917.

Application filed January 31, 1917. Serial No. 145,679.

To all whom it may concern:

Be it known that we, STANLEY LASIEWICZ and PAUL LASIEWICZ, subjects of the Emperor of Austria, residing at Three Lakes, 5 in the county of Oneida and State of Wisconsin, have invented certain new and useful Improvements in Metallic Ties and Rail-Fasteners, of which the following is a specification.

10 This invention relates to certain new and useful improvements in metallic ties and rail fasteners.

The primary object of the invention is the provision of a tie provided with ready 15 means for securing railway rails thereon without the employment of bolts or screws.

A further object of the device is to provide a metallic railway tie having integral positioning means for the outer sides of 20 railway rails and with shiftable wedging devices centrally carried thereon for ready clamping engagement with the inner portions of the rails.

With these general objects in view and 25 others that will appear as the nature of the invention is better understood, the same consists in the novel construction, combination and arrangement of parts herein-after more fully described, illustrated in the 30 accompanying drawings, and then claimed.

In the drawings forming a part of this application and in which like designating characters refer to corresponding parts throughout the several views:—

35 Figure 1 is a side elevation of the device illustrated in its operative arrangement with railway rails shown in section securely positioned thereon.

40 Fig. 2 is a top plan view thereof, the locking member being indicated by dotted lines in its released position.

Figs. 3 and 4 are transverse sectional views taken upon lines III—III and 45 IV—IV respectively, of Fig. 1.

Fig. 5 is a perspective view of one of the rail engaging plates, and,

Fig. 6 is a perspective view of the locking member detached.

The present device broadly consists of a 50 tie 10 preferably formed of metal and having inwardly-extending abutments 11 adjacent the opposite ends thereof for engaging the outer sides of railway rails 12 when arranged upon the tie at the proper gage distance apart in their track formation while locking flange plates 13 are adapted

to engage the inner sides of the rails 12 and retained by a suitable locking member 14.

The abutments 11 present a strong support for the outer sides of the rails 12 fitting against the rail webs 15 and between the treads 16 and base flanges 17 thereof, it being understood that recesses 18 are arranged between the abutments 11 and the main portion of the tie 10 for the reception 65 of the outer flanges of the rails.

The flange plates 13 are of the form best illustrated in Fig. 5 of the drawing, being oppositely arranged, one for each of the 70 rails 12. An outwardly-projecting flange 19 of each plate 13 overlies the inner base flange of the adjacent rail, the plate being flatly positioned upon the upper face of the tie and being of a width corresponding with 75 that of the tie. The plates 13 are provided with inwardly inclined faces 20, the thickness of the inner edges 21 of the plates 13 being greater at one edge as at 22 and by reason of the opposite positioning of the 80 two plates 13 the other inner corners 23 thereof which are of lesser thickness than the corners 22 are arranged at opposite sides of the tie 10.

The cam locking member 14 is in the 85 form of a plate centrally swiveled upon a turn bolt 24 carried by the tie, the opposite end portions 25 of the locking member being beveled forming upwardly and outwardly inclined faces adapted for engaging the 90 faces 20 of the plates 13 during the turning of the locking member 14. When the plates 13 are arranged with their outer flanges 19 overlying the inner base flanges 17 of the rails 12, and with the locking member 95 14 released as shown by dotted lines in Fig. 2 of the drawing, the locking member may be turned in the direction indicated by the arrows in Fig. 2 for bringing the cam-shaped edges 26 of the central lower hub 100 portion 27 of the locking member 14 against the inner edges 21 of the plates 13, thereby assisting in forcing the plates outwardly into engagement with the rails 12. Operating lugs 28 are provided upon the inclined 105 end portions 25 of the locking member 14 adapted for engaging within curved grooves or slots 29 of the plate faces 21 during the closing locking movement of the member 14 being further adapted to force the plates 110 13 outwardly into engagement with the rails 12. It will be understood that the

2
grooves 29 are eccentrically arranged with respect to the pivot 24 whereby the outward movements of the plates are accomplished through the agency of the lugs 28.

5 When the locking member 14 is turned to a position in longitudinal alinement with the tie 10, the opposite edges 30 thereof will be in alinement with the outer faces of the plates 13 as well as the outer sides of the tie 10 and at which times the lugs 28 will 10 be positioned at the inner ends of the slots 29 and rails 12 will be securely locked upon the tie. Perforations 31 may be arranged through the plates 13 and similar perforations 32 through the locking member 14 for 15 the reception of securing bolts 33 to be inserted therethrough and screwed into the tie 10 when the members are in their locking arrangement and at which times the perforations 31 and 32 will be in alinement with 20 each other as well as threaded sockets 34 in the upper face of the tie 10.

A strong mounting and securing member for the rails is arranged in which the rails 25 may be secured to the tie by employing the plates 13 and the locking member 14 without the use of the bolts 33 although the latter are serviceable as a further precaution against any possible release of the rails 12 30 when found desirable.

What we claim as new is:—

1. A device of the class described comprising a tie adapted for mounting rails thereon, integral abutments arranged adjacent the opposite ends of the tie, flanged plates arranged inwardly of said abutments spaced therefrom, a cam locking member centrally swiveled upon the tie intermediate the said plates, and cam connections between the said member and plates.

40 2. A device of the class described comprising a tie, rails mounted thereon, integral abutments carried by the tie adjacent the outer sides of the rails, plates arranged 45 inwardly of the rails upon the tie overlying the base flanges of the rails, and a turn member centrally pivoted upon the tie intermediate the said plates having a hub portion provided with cam edges arranged in 50 operative engagement with the inner edges of the plates during the operation of the device.

3. A device of the class described comprising a tie, rails mounted thereon, integral 55 abutments carried by the tie adjacent the outer sides of the rails, plates arranged in

wardly of the rails upon the tie overlying the base flanges of the rails, a turn member centrally pivoted upon the tie intermediate the said plates having a hub portion provided with cam edges arranged in operative engagement with the inner edges of the plates during the operation of the device, the said plates having curved grooves therein and lugs carried adjacent the opposite ends of the turn member adapted for operative engagement within the said grooves during the wedging operation.

4. A device of the class described comprising a tie, integral abutments arranged adjacent the opposite ends of the tie, rails positioned upon the tie against the said abutments, plates carried by the tie overlying the base flanges of the rails and provided with inwardly inclined upper face portions slanting toward opposite inner corners of the plates when operatively arranged, a turn locking member centrally swiveled between the said plates having beveled end portions with inclined lower faces adapted for overlying the inclined faces of the said plates when in its securing position arranged longitudinally of the tie.

5. A device of the class described comprising a tie, integral abutments arranged adjacent the opposite ends of the tie, rails positioned upon the tie against the said abutments, plates carried by the tie overlying the base flanges of the rails and provided with inwardly inclined upper face portions slanting toward opposite inner corners of the plates when operatively arranged, a turn locking member centrally swiveled between the said plates having beveled end portions with inclined lower faces adapted for overlying the inclined faces of the said plates when in its securing position arranged longitudinally of the tie, the locking member being provided with a hub having cam edges adjacent the inner edges of said plates, the said plates having eccentrically positioned curved slots in the inclined faces thereof, and lugs carried by the inclined faces of the end portions of the locking member adapted for operative positions within the said slots when the device is assembled.

In testimony whereof we affix our signatures.

STANLEY LASIEWICZ.
PAUL LASIEWICZ.
